CLAIM

The ornamental design for a medical connector, as shown and described.

DESCRIPTION

FIG. 1 is a perspective view of a medical connector;
 FIG. 2 is a front view thereof, the rear view thereof (not included) being a mirror image thereof;
 FIG. 3 is a top view thereof;
 FIG. 4 is a right-side view thereof;
 FIG. 5 is a left-side view thereof; and,
 FIG. 6 is a bottom view thereof.

A rear view of the medical connector mirrors the front view.
 The broken lines depict unclaimed portions of the medical connector and form no part of the claimed design.
